SHOWER BATHING APPARATUS

Original Filed June 8, 1928

UNITED STATES PATENT OFFICE.

ROBERT J. GILLESPIE, OF ST. MARTINSVILLE, LOUISIANA, ASSIGNOR OF ONE-FOURTH TO HENRY RANDAZZO, ONE-FOURTH TO AVERY LANDRY, AND ONE-FOURTH TO BERT JACOBSON, ALL OF ST. MARTINSVILLE, LOUISIANA.

SHOWER BATHING APPARATUS.

Application filed June 8, 1928, Serial No. 283,930. Renewed May 22, 1929.

This invention relates to shower bath apparatus.

In many localities, especially in country, suburban and rural districts, homes are generally not provided with bathing facilities, and from the viewpoint of health oftentimes occupants of homes thus located are handicapped and prevented from taking that care of themselves or their bodies which is essential to good health. These localities or districts are not provided with water power systems whereby running water is provided in the homes or outbuildings, with the result that the occupants of these homes are therefore unable to enjoy the privileges and effects inuring from shower bath equipment.

It is therefore one object of the present invention to provide a simple, inexpensive, durable, efficient and effective shower bath apparatus for installation in localities and places where water power plants do not exist and yet obtain highly satisfactory shower bath results.

Another object of the invention resides in the provision of a shower bath apparatus for installation in localities where no water power systems are in operation, and which may be economically and readily installed and operated by all members of the family for effective bathing purposes.

With the above and other objects in view, the invention consists in the construction and novel combination and arrangement of parts hereinafter described, illustrated in the accompanying drawing, and set forth in the claims hereto appended, it being understood that various changes in the form, size, and minor details of construction, within the scope of the claims, may be resorted to without departing from the spirit of the invention or sacrificing any of the advantages thereof.

In the drawing:

Figure 1 is a side elevation of the invention installed and showing the apparatus when not in use.

Fig. 2 is a side elevation showing the invention with the parts positioned for shower bathing purposes.

Fig. 3 is a sectional view on the line 2—2 of Fig. 2.

Fig. 4 is a modified form of means for maintaining the supporting elements of the

water container normally in elevated position.

55

Fig. 5 is a detail sectional view.

Referring now more particularly to the accompanying drawing, the reference character 6 indicates a support composed of wood or other suitable material which may be fastened by screws 7 or otherwise to a wall 8, or other suitable support.

60

The characters 9 and 10 indicate upper and lower brackets, respectively, secured in any suitable manner to the base 6, each including a pair of spaced ears 11, each ear being perforated, and one ear of each pair having its perforation screw threaded to receive the respective screw threaded bolt 13.

65

An arm 14 formed preferably of metal, and which may be tubular or solid, is swingingly mounted in the lower bracket 10. To this end the arm 14 is exteriorly screw threaded at its lower end to receive the interiorly screw threaded sleeve 15, provided with a lug 16 which is perforated to receive the respective bolt which fits in the ears of the lower bracket 10, whereby to swingingly mount the arm from its lower end between the ears of the lower bracket 10.

70

A screw threaded sleeve 18 is fitted on the upper end of the arm 14 and is provided with a lug 19 having a perforation 20. This lug 19 is adapted to support rigidly a substantially semi-circular or other form of support 21. This support 21 is adapted to swingingly suspend a bucket or other water containing receptacle 22, and has a perforation 23 through which a threaded bolt 24 may be passed and a firm and rigid connection between the support 21 and lug 19 effected by means of a nut 25 threaded on the bolt 24, as shown.

80

The receptacle 22 may be of metal or any other suitable material, and it is swingingly suspended from the support 21 in any suitable manner, but, as shown, it is supported preferably by means of threaded bolts 26 which pass through the sides of the receptacle 22, nuts 27 being threaded on the bolts 26 to prevent accidental disconnection of the receptacle from its support.

90

Fitted in any suitable manner, and preferably centrally of the receptacle, is a valved sleeve 28 to which a hose 29 may be secured in any suitable manner. A spray nozzle 30

100

105

is secured to the outer end of the hose 29. When the receptacle is filled with water, it is obvious that by manipulating the valve handle 31 to open the valve, the water will 5 flow freely from the receptacle and through the hose and the nozzle. The receptacle may contain any amount of water, say for instance, four gallons, more or less, and the device may be mounted at any suitable elevation.

10 The arm 14 is preferably maintained in upright position so as to be normally out of the way, and when swung downwardly it is preferred that it not swing beyond a substantially horizontal position and at a suitable 15 height to enable the user to stand under the water receptacle. Accordingly, there is secured to the arm a clamp or other suitable device 32 in which is pivoted one end of a link 33 which is pivoted at its outer end, as 20 at 34, to the outer end of a second link 35, pivoted between the ears of the upper bracket 9 by means of a threaded bolt 13 operating in the ears of the upper bracket 9 and threaded in the threaded perforation of one of the ears 25 of the bracket 9.

The link 35 is provided at its inner end with a laterally offset hook 38 which is adapted to engage over the upper edge of the link 33 as the links 33 and 35 align and lock the pivot 30 point 34 slightly beyond dead center so as to prevent accidental folding of the links and thereby prevent an accidental elevation of the arm 14 from a substantially horizontal to a substantially vertical position.

35 It will be understood that the arm 14 is normally maintained in a substantially vertical position with the links folded, and when the arm 14 is swung to a substantially horizontal position, and the links 33 and 35 there- 40 by unfolded, until the hook 38 locks the links to prevent accidental upward movement of the arm, to unlock the locking connection between the links 33 and 35, that is to say, to release the locking hook 38 from engage- 45 ment with the link 33, it is simply necessary for the user or other person to strike a slight blow against the under side of the link 33 to thereby break the locked joint between the links, rendering it an easy matter to swing 50 the arm to its substantially vertical position.

A coiled spring 39, secured to the base 6 at 40, may be utilized to exert pressure at the point 41 against the arm 14 to facilitate the upward movement of the arm and to maintain 45 the arm in its substantially vertical position with the receptacle empty or containing water, and yet, whether the receptacle contains water or not, the locking joint between the links 33 and 35 is such as to overcome the 50 tension of the spring 39 when the arm is locked in substantially horizontal position.

Instead of the spring 39, other means may be employed for exerting pressure against the arm 14 to normally maintain the latter in its 55 substantially vertical position. For instance,

by way of modification, it will be seen by reference to Fig. 4 of the accompanying drawing that a weight 42 of any suitable character may be connected by a cable 43 passed over a pulley 44 and connected to the upper end 70 of the arm 14. When the weight is employed, the base is made longer and extends upwardly to or adjacent the end of the swinging arm so that said pulley may be mounted directly in the base. Except for the substitution 75 of a weight controlling means for the arm 14 to maintain the latter normally in vertical position, and the lengthening of the base, the apparatus is not altered.

Whether a spring or a weight be employed 80 for maintaining the arm 14 normally in vertical position, it may be desired at times to have associated with the apparatus a curtain, which is shown in part at 45, and this curtain if used is preferably parted at the front. 85 This curtain is suspended from a curtain supporting element 46 in any suitable manner, and this curtain supporting element 46 is secured by means of suitable fastenings 47 to the upper end of the base 6 above the 90 upper bracket 9.

From the foregoing it will be seen that there is provided a simple and inexpensive apparatus particularly adapted for use in country or outlying districts, and through the 95 instrumentality of which persons not at present provided with bathing apparatus may possess themselves of and enjoy the effects of shower bathing at comparatively little expense, and by virtue of which persons not 100 equipped at all with bathing apparatus will be enabled to utilize bathing facilities even though their homes or localities are not provided with water power systems.

What is claimed is:

1. In an apparatus of the character described, a base, an arm pivotally mounted on the base to swing in a vertical plane, links pivotally connected at their inner ends and at their outer ends pivoted respectively one to the base and the other to the arm, the links folding and unfolding with the movements of the arm, a supporting element connected to the outer end of the arm, a receptacle swingingly suspended from said supporting element, means to maintain the arm and receptacle in elevated position, and means connected to one of said links and co-operating with the other of said links to maintain the arm and receptacle lowered 115 against the elevating action of the aforesaid means.

2. In an apparatus of the character described, a base, an arm pivoted thereon to swing in a vertical plane and to assume a substantially vertical position and also to assume a substantially horizontal position, links pivoted together at their inner ends and at their outer ends pivoted respectively one to the base and the other to the arm, a sup- 125 130

porting element connected to the outer end of the arm, a receptacle swingingly suspended from said supporting element, means to maintain the arm normally in substantially vertical position and thereby elevate the receptacle, and means co-acting with the links to maintain the arm in substantially horizontal position and the receptacle lowered against the elevating action of the aforesaid 10 means, the receptacle having a valved outlet, and a nozzle operatively connected to said outlet.

3. In an apparatus of the character described, a base, upper and lower brackets secured to the base, an arm pivotally connected to the lower bracket and adapted to swing in a vertical plane, links pivotally connected together at their inner ends and at their outer ends pivoted respectively one to the upper 15 bracket and the other to said arm below the upper end of the latter, a supporting element connected to the outer end of the arm, a receptacle pivotally suspended from said supporting element, the receptacle having a valved discharge outlet, means to maintain the arm and receptacle normally in elevated position, the arm and receptacle being adapted to be lowered against the action of said means, and a locking device adapted to maintain the arm and receptacle in their lowered 20 positions against the action of said elevating means.

4. In an apparatus of the character described, a base, upper and lower brackets secured to the base, an arm pivotally connected to the lower bracket and adapted to swing 25

in a vertical plane, links pivotally connected together at their inner ends and at their outer ends pivoted respectively one to the upper bracket and the other to said arm below the upper end of the latter, a supporting element connected to the outer end of the arm, a receptacle pivotally suspended from said supporting element, the receptacle having a valved discharge outlet, means to maintain the arm and receptacle normally in elevated position, the arm and receptacle being adapted to be lowered against the action of said means, a locking device adapted to maintain the arm and receptacle in their lowered 30 positions against the action of said elevating means, a curtain supporting element secured to said base, and a curtain suspended from the curtain supporting element.

5. In an apparatus of the character described, an arm pivotally mounted to swing in a vertical plane, a receptacle supporting element secured to the outer end of the arm, a receptacle swingingly connected to said supporting element and provided with a valved outlet, means whereby to maintain the arm normally in a substantially vertical position with the receptacle elevated therewith, and means to maintain the arm lowered in a substantially horizontal position with the receptacle lowered therewith against the action of said means to normally elevate the arm to said vertical position.

In testimony whereof I have hereunto set my hand this 6th day of June, 1928.

ROBERT J. GILLESPIE.
